(57) **CLAIM**

The ornamental design for a display screen or portion thereof with graphical user interface, as shown and described.

DESCRIPTION

FIG. 1 is a front view of a display screen or portion thereof with graphical user interface; and,

FIG. 2 is a front view of a second embodiment thereof. The broken lines shown in FIGS. 1 and 2 represent portions of the display screen or portion thereof with graphical user interface that form no part of the claimed design.

1 Claim, 2 Drawing Sheets
